UNITED STATES PATENT OFFICE

118,037

DESIGN FOR A TEXTILE FABRIC OR SIMILAR ARTICLE

Achille Domen, Roubaix, France

Application December 28, 1938, Serial No. 82,019

Term of patent 7 years

To all whom it may concern:

Be it known that I, Achille Domen, a citizen of France, residing at Roubaix, France, have invented a new, original, and ornamental Design for Textile Fabric or Similar Article, of which the following is a specification, reference being had to the accompanying drawings, forming part thereof.

In the accompanying drawings:

Fig. 1 is a plan view of the fabric showing my design, the irregular line surrounding the oval design indicating background forming part of the design.

Fig. 2 is an enlarged view of a lefthand upper

portion of the oval wreath-like design, the weave of the fabric running from the inner background through the wreath-like design into the outer background.

The characteristic feature of the design consists of a group of floral elements on a background providing contrasting inner and outer portions with a wreath-like oval design within the region between the inner and outer portions.

I claim:

The ornamental design for textile fabric or similar article, substantially as shown and described.

A. DOMEN.
